(57) **CLAIM**

The ornamental design for a tire, as shown and described.

DESCRIPTION

FIG. 1 is a front-right-top perspective view of a tire showing my new design;

FIG. 2 is a front elevational view thereof, the opposite side being a mirror image; and,

FIG. 3 is a right elevational view thereof, the opposite side being a mirror image.

The dash/dot/dash broken lines seen at the bead of the tire depict the boundary of the claim and form no part of the claimed design.
